STRAP FASTENING TOOL

Burnie M. Craig, Pasadena, Calif., assignor to
Michael J. McAneny, Buffalo, N. Y.

Application June 2, 1947, Serial No. 751,912

13 Claims. (Cl. 81—9.1)

1

This invention relates generally to certain new and useful improvements in hand-operated tools for facilitating the banding or strapping of packages by metallic straps and buckles.

It has for one of its objects to provide a reliable and efficient tool of this character which is designed and constructed for use on all types and shapes of packages to be shipped, and which in a given operative stroke tensions or tightens the strap about the package, cuts the strap to the length required, and finally forms, couples and seals the end of the strap to the buckle.

Another object of the invention is the provision of a strap-fastening tool which is so designed as to adapt it for use with thin strap material, which can be readily brought into and out of operative relation to a strap to be fastened, and which embodies in a unit mechanism controlled by an actuating lever or handle the functions of tensioning, cutting, forming and sealing in sequence.

A further object is to provide the tool with simple and effective means for holding the strap in its tensioned, package-encircling position and at the same time relieve the free end of the strap of any tension thereon so as to enable it to be readily and properly formed or bent and properly presented into coupling engagement with the buckle.

A still further object of the invention is to provide novel gripping means for exerting a pull or tension on the strap about the package in such a manner that when the actuating lever is moved in one direction it positively grips the strap and when partially moved in the opposite direction it is released from the strap prior to taking another bite or hold on the strap, if required.

Other features of the invention reside in the construction and arrangement of parts herein-after described and particularly pointed out in the appended claims.

In the accompanying drawings:

Figure 1 is a perspective view of my tool showing the same in operative relation to a package. Figure 2 is an enlarged, fragmentary side elevation thereof. Figure 3 is an enlarged, fragmentary longitudinal section thereof taken on line 3—3, Figure 1. Figure 4 is a cross section taken on line 4—4, Figure 2. Figure 5 is a fragmentary top plan view of the front end of the tool showing the buckle-rest and strap-clamping mechanism. Figure 6 is a front end view of the same. Figure 7 is a cross section taken on line 7—7, Figure 5. Figure 8 is a detail side view showing the relation of the buckle and strap portions to the

2
tool. Figure 9 is a fragmentary sectional elevation of the buckle and strap-clamping assembly. Figure 10 is a fragmentary bottom plan view of such assembly. Figure 11 is an enlarged, fragmentary longitudinal section, similar to Figure 3, showing the tool in its strap-tensioning position. Figure 12 is a fragmentary side elevation, partly in section, showing the tool in its strap-cutting and forming position. Figures 13, 14 and 15 are fragmentary longitudinal sections, similar to Figure 3, showing, respectively, the tool in its strap-cutting and forming positions, its position for bending the end of the strap over and into coupling relation with the buckle, and the final position of sealing the strap to the buckle. Figure 16 is a perspective view of the buckle. Figure 17 is a side elevation of the buckle and the co-acting strap portion, showing the terminal end of the strap bent about and inserted in the lower retaining loop of the buckle.

Similar characters of reference indicate corresponding parts throughout the several views.

In the preferred embodiment of my invention shown in the drawings, it consists of an open-like, rectangular frame composed of spaced, longitudinal side rails 15, 15, a transverse tie member 16 disposed between the rear ends of said rails and suitably shaped to provide a laterally-opening guide slot 16^a therein for bringing the tool into and out of engagement with the package band or strap to be operated upon by the tool as well as to provide a supporting foot for the rear end of the tool, and front extensions 17, 17 of substantially T-shape in plan bolted or otherwise secured to the outer sides of said rails and on which the strap-clamping and buckle-rest assembly of the tool are mounted. For the purpose of manipulating the tool when buckling a retaining strap about a package or the like, a suitable handle 18 is provided which extends rearwardly from the frame and is fixed at its forward end in the tie member 16. The position of the tool in use is depicted in Figure 1, where 19 indicates the package to be banded, 20 indicates a metallic strap or band about to be buckled and sealed about the package by the tool, and 21 indicates a completely sealed strap secured at its ends to a buckle 22.

This buckle is blanked and formed from a single piece of rectangular-shaped metal or the like folded upon itself and, as shown in Figures 16 and 17, has longitudinal flanges 23 at its opposite sides to be received by the tool in operative relation thereto, a central longitudinal passage 24 through which the opposing free ends

of the strap are threaded in overlying relation, and front and rear portions offset from the top and bottom sides of the buckle to provide arched loops or straps 25 and 26, respectively, which are inclined slightly to the plane of the buckle. One end of the strap 20 to be applied to the package is extended through the buckle-passage 24 and folded or reversely bent about the underside of the buckle, while the opposing overlying end of the strap is extended in the reverse direction through the buckle-passage. It is in this loop-like position of the strap about the package that the tool is brought into operative relation therewith and with its buckle to pull the strap snugly and tightly about the package in one stroke-like operation of the tool and hold it in that position with the free end of the overlying portion of the strap free of tension, after which the steps of cutting such untensioned free end, forming or bending it over the buckle, and finally sealing the strap-ends and buckle are performed in a second stroke-like operation of the tool. That end of the strap bent about the buckle may assume the position shown in Figures 11 and 12, or its free end may be inserted into the buckle-loop 26, as shown in Figure 17.

Guided for lateral adjustment on the lower ends of the transverse, substantially medial flanges 27 of the side rail extensions 17, 17, and which flanges terminate in spaced relation at their opposing inner ends to clear the side edges of the strap, as shown in Figures 5, 7, and 10, are companion block-like members or buckle-rests 28 having hook-like lips 29 at their lower ends for detachable gripping engagement with the front ends of the side flanges 23 of the buckle 22, in the manner shown in such figures and also in Figures 11 and 12. By preference, the lower guide portion 30 of the flanges 27 are substantially T-shaped and the companion interfitting grooves 31 of the buckle-rests 28 are of like shape. Each of the latter is set in its adjusted position, as determined by the size of the buckle, by an adjusting screw 32 mounted transversely in the corresponding side rail extension and engaging a threaded opening in the block member, in the manner shown in Figure 7.

Disposed forwardly of the buckle-rests 28 in parallel relation thereto and mounted for movement toward and from each other between the front ends of the side rail extensions 17, 17 are strap-engaging jaws or blocks 33 having lugs or projections 34 at the bottom sides of their inner or opposing ends for releasable supporting engagement beneath the marginal side edges of the strap 20, as shown by dotted lines in Figure 6. These jaws are guided at their lower ends on a transverse rod 35 supported at its ends in the side rail extensions and rising from the other side of each jaw is an upright flange 36. A rotatable cylindrical cam 37 is journaled on each jaw-flange 36, but held against axial displacement relative thereto, and an axle 38 supported at its ends in the side rail extensions serves, jointly with the guide rod 35, to properly guide the jaws and their companion cams bodily toward and from each other. Each cam has a spiral or diagonal groove 39 disposed part-way about its periphery and extending into the same is a coupling pin 40 projecting forwardly from the upper end of the companion or adjoining buckle-rest 28, as shown in Figures 5 and 9. A crank handle or actuating knob 41 is connected jointly to the companion cams 37 by radial arms 42 each fixed at one end to its cam and extend-

ing at its other end through a longitudinal slot 43 formed in the handle and terminating at such end in an outwardly-bent shank 44 free to move or slide in a longitudinal opening 45 formed in the handle and in communicating relation with said slot. A cover or hood 46 extends over the cams 37 and associated parts and it has a forwardly and downwardly converging opening 47 therein through which the handle-arms 42 extend and along the edges of which they are guided. In the released or non-strap engaging position of the jaws 33, the operating handle assumes the upright position shown in Figures 3 and 6. Upon turning this handle forwardly to the substantially horizontal position shown in Figures 1 and 9, the cams 37 are turned therewith and because of the cam-groove and coupling pin construction 39, 40, the cams and their companion jaws 33 are compelled to contract or shift toward each other to bring the jaw-lugs 34 beneath and in supporting engagement with the marginal edges of the strap. In this position of the parts, the lower adjoining portions of the jaw-blocks above lugs 34 partially overhang the top or outer face of the strap in the manner shown in Figures 6 and 9.

Each strap-engaging jaw 33 is also provided with means for effectually clamping that portion of the strap forwardly of the buckle, as supported from beneath by the jaw-lugs 34, to the tool during the operation of pulling or tensioning the strap snugly about the package and subsequently sealing it to the buckle. This clamping action, furthermore, is performed simultaneously with that of the movement of the cams and the jaws to their strap-engaging position. To this end, a vertically-swinging gripping dog 48 is fulcrumed at 49 to the inner face of each jaw-block 33 and rearwardly of the cam-axle 38, a recess 50 being provided to receive it so the dog is in the operating path of the companion cam 37 and in a plane intersecting the companion strap-supporting jaw-lug, as shown in Figures 6 and 9. This dog is preferably in the form of a two-armed lever with one arm having gripping teeth 51 at the lower end thereof and the other arm being engaged by a spring 52 seated in an adjoining portion of the companion jaw-block and constantly urging the dog to seek a strap-gripping position. Each cam governs the movement of the companion dog into and out of its gripping position, and in the released position of the operating handle 41, shown in Figure 3, the respective cams 37 engage the dogs in a manner to project them in a direction to bring their gripping teeth 51 above and clear of the strap. On its periphery each cam has a flat or chordal face 53 which functions, in the operative or gripping position of the handle 41, to allow the companion dog 48 to be displaced by its spring 52 in a direction to bring its teeth into gripping engagement with the strap, as shown in Figures 9 and 15; these dogs together with the jaw-lugs 34 constituting a vise for gripping the strap and retaining the tool thereon during the subsequent operations to be performed. It should be noted here that the overlying portion of the strap which extends rearwardly or toward the buckle from the dog-gripping point is untensioned and free to be folded for coupling engagement with the buckle in a manner which will hereinafter appear.

Operatively disposed for longitudinal reciprocating movement on the side rails 15, 15 between the tie member 16 and the buckle rests 28 is a

strap-engaging mechanism which serves to grip and pull or tighten the strap about the package, to cut the overlying stretch of the strap at a point rearwardly of the buckle, to form or shape such resulting rearward extension of the strap and fold and direct it into coupling engagement with the buckle, and to finally seal the buckle and strap to provide a strong connection. This mechanism is further so constructed as to perform the tightening operation of the strap about the package when moved in one direction, while the remaining operations are performed when the mechanism is moved in the opposite direction. This mechanism is preferably constructed as follows:

The numeral 54 indicates a slide-member of substantially U-shape in plan and grooved at its opposite sides for guiding engagement with the side rails 15, 15 of the tool-frame, as shown in Figures 1 and 4. One side wall of this slide member extends somewhat below that of its opposite side and has fastened thereto a horizontally-disposed cutter block or anvil 55 extending the full length of such member and bridging the open bottom thereof. The opposite wall of the slide member has an upright recess 56 in the inner face thereof at its front end for a purpose which will later appear. The bottom side of the cutter block is substantially in the same plane as the buckle-rest lips 29 and jaw-lugs 34, and in operation the tool rests on the forwardly-extending or lower stretch of the strap 20 while the rearwardly-extending or overlying portion of the strap passes over the top side of such block in the manner shown in Figure 3; the tool being brought laterally into and out of operative relation with the strap. At its front end the cutter block has a pointed nose 57 and immediately to the rear and in the top side thereof has a forwardly-sloping face 58 terminating at its front end in a like-facing shoulder 59. Immediately to the rear of this sloping face is a transverse recess 60, all of these parts of the cutter block functioning during the forming and cutting operations on the strap.

Disposed in the open space of the slide member 54 and pivoted at its lower end at 61 thereto is a vertically-swinging rock member 62 which cooperates with the cutter block in gripping, forming, cutting and sealing the strap to the buckle. At its lower rear or corner end this rock member is serrated, as indicated at 63, so that when it is rocked rearwardly it serves as a gripping pawl by gripping the top side of the strap and clamping it firmly against the top of the cutter block or anvil 55. Forwardly of this gripping pawl portion of the rock member and extending transversely of the lower side thereof is a downwardly opening notch or groove 64 for receiving the cut or sheared end of the strap in the manner shown in Figure 13. This groove defines along the rear side thereof a cutting or shearing edge 65 which cooperates, on the forward rocking stroke of the rock-member, with the opposing front edge defined by the recess 60 in the cutter block to sever the strap to the required length for banding the package. Along its lower front edge the groove 64 defines a downwardly and rearwardly directed, substantially V-shaped die portion 66 which cooperates with the sloping face 58, shoulder 59 and pointed nose 57 of the cutter block, upon the completion of the forward rocking stroke of the rock member, to upwardly bend or form the severed end portion of the strap in the manner shown in Figure 12. At its lower front or corner end the rock member 62 has a

second, substantially V-shaped die portion 67 which functions to press and seal the upwardly-bent end of the strap downwardly in arched-like fashion against and into coupling engagement with the buckle, as seen in Figure 15. The upper end of this second die portion terminates in a forwardly-facing nib or projection 68 which functions at a predetermined time in the strap-bending operation to contact the upwardly-bent tip end of the strap and, upon a forward movement of the slide and rock member, impart a slight lift thereto in order to insure a positive subsequent engagement of the die portion 67 of such rock member with the strap-end to force it into coupling relation with the buckle.

Pivoted at 69 in the slide-recess 56 adjacent the opposing outer wall of the rock member 62 is a vertically-swinging latch 70 having a spring 71 abutting the same for constantly urging it in the forwardly-swinging direction, shown in Figure 2, with the lower rear edge of the latch abutting the opposing inclined face of the recess. A pin 72 projects laterally from one side of the rock member for engagement with this latch to govern the rocking movements of such member during the operation of the tool. When the slide member 54 approaches the forward end of its stroke, shown in Figures 12 and 13, the front end of the latch 70 abuts the opposing rear wall of the rail-flange 27 to cause such latch to rock rearwardly to release the coupling pin 72 therefrom, whereupon the rock member 62 is free to be rocked in a rearward direction by the manipulation of the handle 73 to cut the strap 20 to the proper length as well as form its sheared end in the manner depicted in Figure 13.

The slide and rock members 54, 62 are shifted or operated manually to their respective operating positions by means of a vertically-swinging operating handle or lever 73 pivoted at its front end at 74 between a pair of lugs 75 rising from the rock member and including a pair of toggle links 76 pivoted at one end at 77 to said operating lever outwardly of its pivot 74 and at their other ends at 78 to the upper end of the tie member 16. Between the latter and the slide member 54 is a resilient stop for cushioning its rearward movement, such stop preferably consisting of a plunger 79 guided in the projected front end of the handle 18 and backed by a spring 80, as shown in Figure 3. This resilient stop also tends to urge the slide member forwardly from its retracted position and thereby facilitates the rapid operation of the tool during the strap-tightening operation.

Operation of the device may be briefly explained as follows: A metal strap or band 20 extending through the buckle and with its end attached to the buckle as in Fig. 17, is placed around the object to be bound as illustrated in Fig. 1. The tool, with cam operating lever 42 in the position illustrated in Figs. 3 and 6 in which the strap engaging jaws are opened and pawls 48 are depressed by cam 37, is placed over strap 20 and buckle 22 is engaged with flange portions 23 between buckle rests 28 and lips 29 and with the portion of the strap extending through the buckle passing through slot 16a at the rear of the tool and overlying anvil 55 of slide 54. Cam lever 42 is turned to the position illustrated in Fig. 2 shifting strap gripping members 33 from their open full line position to the strap engaging position dotted line position with lugs 34 engaged beneath the strap as illustrated in Fig. 6. In this position pawls 48 are urged by

springs 52 into engagement with the strap, the pawl lever arms having entered the chordal recesses of the cams. This causes the tool to be retained and the strap to be engaged between the gripping dogs 48 and lugs 34 against withdrawal of the strap from the buckle but permits a drawing movement of the strap through the buckle by the tool.

Following engagement of the tool with the strap and buckle, the handle 73 is swung to cause the pawl end 63 of rocker 62 to be elevated above the strap and the slide 54 to slide forwardly a distance determined by the extent of movement of the handle. Swinging of the handle in a reverse direction causes pawl 63 to grip the strap against anvil 55 and slide 54 is forced rearwardly to draw the strap through the buckle and tension it, the tension thereof being held beyond the buckle, by engagement of dogs 48. This operation may be repeated as desired to effect complete tightening of the strap through the buckle and around the object. In the strap tensioning movements of the slide and rock member latch 70 is in engagement with pin 72 limiting forward rocking movement of rocker 62 but when the strap is sufficiently tensioned, and severing and fastening of the untensioned cut end to the buckle is desired, the slide is caused to be moved to a forward position wherein latch 70 is tripped by engagement with the rail flange 21 to allow further rocking of member 62 by the handle to cut the strap and bend its end upwardly by the cooperating cutting and bending die portions of the rocker 62 and anvil 55. After cutting and forming the strap, slide 54, together with rocker 62, is moved by the handle rearwardly until the forward end portions 67 and 68 are disposed rearwardly of the bent end of the strap, after which the slide is again advanced to cause rocker portion 68 to initiate an upward folding movement of the strap and portion 67 to fold the strap end over the upper side of the buckle and force the end of the strap under arch 25 of the buckle. In this movement, the untensioned severed end of the strap is in effect bent around the end of the buckle and ironed into substantially flat engagement with the buckle with the end of the strap confined by the buckle arch.

The strap having been tensioned, cut, formed and folded over and into the buckle, cam operating lever 42 is swung upwardly to its original position and the machine or tool is released from strap and buckle engagement.

I claim as my invention:

1. A strap fastening tool of the character described, comprising a frame having means thereon to detachably receive a buckle to which one end of a banded strap is connected, said buckle-receiving means including laterally-adjustable members having rests thereon for supporting the marginal side edges of the buckle, laterally-displaceable means mounted on said frame forwardly of said buckle-receiving means and adapted to receive and clamp thereto the other end of the strap to be fastened to the buckle, and means mounted on said frame and operatively connected to said strap-receiving means for actuating the same toward and from each other into and out of the engagement with the marginal side edges of the strap.

2. A strap fastening tool of the character described, comprising a frame having means thereon to detachably receive a buckle to which one end of a banded strap is connected, laterally-displaceable means mounted on said frame for-

wardly of said buckle-receiving means and adapted to detachably receive the other end of the strap to be fastened to the buckle, gripping elements mounted on said strap-receiving means for releasably clamping such strap portion thereto, and means mounted on said frame and operatively connected to the strap-receiving means for actuating the same into and out of receiving relation with the strap and the gripping elements

10 into and out of clamping relation with the strap.

3. A strap fastening tool of the character described, comprising a frame having means thereon to detachably receive a buckle to which one end of a banded strap is connected, means mounted on said frame forwardly of said buckle-receiving means for movement laterally thereof into and out of receiving relation with the other end of the strap, spring pressed gripping elements applied to said strap-receiving means in 20 correlation thereto for releasably clamping such strap portion thereto, and manually-controlled actuating means for the strap-receiving means and the gripping elements for causing the projection of the strap-receiving means into receiving 25 engagement and for releasing the gripping element for gripping engagement with the strap when moved in one direction and the retraction of such parts to their released positions when moved in the opposite direction.

30 4. A strap fastening tool of the character described, comprising a frame having means thereon to detachably receive a buckle to which one end of a banded strap is connected, means mounted on said frame forwardly of said buckle-receiving means for movement laterally thereof into and out of receiving relation with the other end of the strap, vertically-displaceable gripping elements pivoted on said strap-receiving means for releasably clamping the strap thereto, springs 35 engaging said elements for normally urging them to a clamping position, and manually-actuated, oscillatory and laterally-movable means operatively connected to said strap-receiving means for causing their lateral displacement into and out of receiving relation with the strap, said oscillatory means having portions in governing relation with said gripping elements for controlling their simultaneous companion displacement into and out of clamping engagement with the strap.

30 5. A strap fastening tool of the character described, comprising a frame having means thereon to detachably receive a buckle to which one end of a banded strap is connected, means mounted on said frame forwardly of said buckle-receiving means for movement laterally thereof into and out of receiving relation with the other end of the strap, vertically-displaceable gripping elements pivoted on said strap-receiving means for releasably clamping the strap thereto, springs 55 engaging said elements for normally urging them to a clamping position, manually-actuated oscillatory and laterally-movable means operatively connected to said strap-receiving means for causing their lateral displacement into and out of receiving relation with the strap, said oscillatory means having portions in governing relation with said gripping elements for controlling their simultaneous companion displacement into and out of clamping engagement with the strap, and an operating member for said oscillatory and laterally-movable means including radial arms fixed at one end to such means and a handle slotted to receive the other ends of said arms 60 to permit the movement of said arms laterally

75 to permit the movement of said arms laterally

toward and from each other and relative to said handle.

6. A strap fastening tool of the character described, comprising a frame, buckle-receiving members mounted on said frame for lateral adjustment toward and from each other and having rests at their lower ends for supporting the marginal side edges of a buckle, strap-engaging members mounted on said frame forwardly of said buckle-receiving members for lateral displacement toward and from each other into and out of receiving engagement with the strap, spring pressed gripping elements pivoted on said companion strap-engaging members for releasably-clamping the strap thereto, and means for actuating said strap-engaging members into and out of their strap-engaging positions and for controlling the displacement of their gripping elements into and out of their clamping positions, said means including spirally-grooved cams operatively connected to said members to travel laterally therewith and free to turn relatively thereto, coupling pins projecting from said buckle-receiving members and engaging the grooves of the companion cams, and an operating handle jointly connected to said cams for turning them in one direction or the other to correspondingly displace the strap-engaging members into and out of their operative position, said cams having portions thereon in governing relation with said gripping elements for causing their simultaneous displacement into and out of clamping engagement with the strap.

7. A strap fastening tool of the character described, comprising a frame having a handle at one end and means at its opposite end to detachably receive a buckle to which one end of a strap is connected, releasable clamping means applied to said frame forwardly of said buckle-receiving means for guidingly engaging and gripping the other end of the strap, a strap-engaging slide and rocker mechanism guided for longitudinal movement on said frame to the rear of the buckle-receiving means and including complementary elements thereon for clamping the strap thereto, for cutting the strap end to the rear of the buckle and for forming and sealing such end over the buckle, and a vertically-swinging lever operatively connected to the frame and said mechanism for imparting a fore and aft sliding and rocking action thereto for causing the clamping of the strap on its forward movement and for causing the forming and sealing operations on its rearward movement.

8. A strap fastening tool of the character described, comprising a frame having a handle at one end and means at its opposite end to detachably receive a buckle to which one end of a strap is connected, releasable clamping means applied to said frame forwardly of said buckle-receiving means for guidingly engaging and gripping the other end of the strap, a strap-engaging slide and rocker mechanism guided for longitudinal movement on said frame to the rear of the buckle-receiving means and including complementary elements thereon for clamping the strap thereto, for cutting the strap end to the rear of the buckle and for forming and sealing such end over the buckle, and a vertically-swinging lever operatively connected to said mechanism for imparting a fore and aft sliding and rocking action thereto for causing the clamping of the strap on its forward movement and for causing the forming and sealing operations on its rearward movement, said lever being piv-

oted at its free end to the rocker portion of said mechanism and link-connected outwardly of such pivot to the rear end of said frame.

9. A strap fastening tool of the character described, comprising a frame having a handle at one end and means at its opposite end to detachably receive a buckle to which one end of a strap is connected, releasable clamping means applied to said frame forwardly of said buckle-receiving means for guidingly engaging and gripping the other end of the strap, a strap-engaging slide and rocker mechanism guided for longitudinal movement on said frame to the rear of the buckle-receiving means and including complementary elements thereon for clamping the strap thereto, for cutting the strap end to the rear of the buckle and for forming and sealing such end over the buckle, the rocker portion of said mechanism being pivoted on the slide portion thereof for relative vertically swinging movement to impart a clamping action on the strap when rocked in one direction and to impart a cutting and forming action on that portion of the strap rearwardly of the buckle when rocked in the reverse direction, and manually-operated lever and latch means operatively connected to said frame and said slide and rocker mechanism for imparting relative fore and aft sliding and rocking movements thereto.

10. A strap fastening tool of the character described, comprising a frame having a handle at one end and means at its opposite end to detachably receive a buckle to which one end of a strap is connected, releasable clamping means applied to said frame forwardly of said buckle-receiving means for guidingly engaging and gripping the other end of the strap, a strap-engaging slide and rocker mechanism guided for longitudinal movement on said frame to the rear of the buckle-receiving means, the slide portion of such mechanism being substantially U-shape in plan and having an anvil-like member bridging the lower end thereof over which the strap is adapted to extend, the rocker portion of such mechanism being pivoted adjacent its lower end in the U-space of the slide portion for vertically-swinging movement, the opposing faces of said anvil-like member and said rocker having complementary strap-clamping portions thereon, engageable with each other when the rocker is swung in one direction and having complementary shearing and die-forming portions for cutting and forming the end of the strap when the rocker is swung in the reverse direction, and manually operable lever means connected to said rocker portion and said frame for sliding and operating the rocker mechanism.

11. A strap fastening tool of the character described, comprising a frame having a handle at one end and means at its opposite end to detachably receive a buckle to which one end of a strap is connected, releasable clamping means applied to said frame forwardly of said buckle-receiving means for guidingly engaging and gripping the other end of the strap, a strap-engaging slide and rocker mechanism guided for longitudinal movement on said frame to the rear of the buckle-receiving means, the slide of said mechanism having an anvil-like member at its lower end over which the strap extends and provided at its front end with a nose for bending the free end of the strap over the buckle, and the rocker of said mechanism having a die portion complementary to said anvil nose for bending and pressing the free end of

the strap in sealing relation to the buckle, said rocker having a second die portion thereon engageable with the tip of the bent end of the strap to impart a slight lift thereto for properly presenting the resulting bend in the strap between the complementary die portions of the rocker and anvil member, and manually operable lever means connected to said rocker portion and said frame for sliding and operating the rocker mechanism.

12. A strap fastening tool of the character described, comprising a frame having a handle at its rear end, a strap-clamping means at the front end of the frame, means on said frame for detachably supporting a buckle rearwardly of the strap-clamping means, a slide member engageable with the strap and guided for longitudinal movement on the frame toward and from the buckle-supporting means, a rocker member pivoted at its lower end to said slide member to swing vertically, complementary elements on said slide and rocker members for jointly operating on the free end of the strap to cut, form and seal the same with the buckle, a vertically swinging operating lever pivoted at its front end to the upper end of said rocker member for actuating the latter and the slide member, a link pivoted at one end to the rear end of said frame and at its other end to said lever outwardly of its pivot, a latch fulcrumed on said slide member and having a spring bearing thereon for normally urging it to a forwardly-projected position, and a pin applied to said rocker member and movable therewith into and out of coupling engagement with said latch.

13. A strap fastening tool of the character described, comprising a frame having means at its head end for guiding engagement with the strap and for supporting a buckle in operative relation thereto and having means at its rear end for guiding engagement with the straps, clamping means applied to the head end of said frame for releasably gripping the strap between it and said

head end guiding means, a slide member guided on said frame between the front and rear ends thereof and including a die portion over the top and bottom faces of which the opposing strap ends are adapted to overlie, a rocker member fulcrumed on said slide in correlation with the die portion thereof and having gripping, cutting, forming and sealing elements thereon, a releasable latching connection between said slide and rocker members, and an actuating means operatively connected to said frame and to said slide and rocker members for governing said latching connection and causing the actuation of the rocker member in one direction for effecting the gripping and tensioning of the strap about the package when such means is moved in one direction and for causing the actuation of the rocker member and the slide member in the reverse direction for effecting the cutting, forming and sealing of the cut end of the strap over and in coupling engagement with the buckle when said actuating means is moved in the opposite direction.

BURNIE M. CRAIG.
